UNITED STATES PATENT OFFICE.

CESARE BARBIERI, OF NEW YORK, N. Y., ASSIGNOR TO THE VORTEX MFG. CO.,
A CORPORATION OF ILLINOIS.

PAPER CUP.

Continuation of applications filed July 3, 1922, Serial Nos. 572,518 and 572,519. This application filed October 2, 1925. Serial No. 60,121.

This invention relates to paper cups of the sort that are intended to be folded flat for storage or transportation and that when in use are rounded into approximately conical form.

It is an object of this invention to provide a cup that may be quickly and easily manufactured from a single blank and that will not be likely to work open at any place.

10 It is a further object of this invention to provide such a cup without any pointed places in the parts secured together by adhesive so that there will be no points likely to turn up or work loose.

15 It is a further object of this invention to provide a blank for such cups with a notch therein so located that the folds necessary to make the cups from the blank shall not intersect.

20 It is a further object of this invention to make a cup which is less likely to leak than the cups heretofore provided.

25 It is a further object of this invention to provide a blank that can be readily and accurately positioned in the cup forming machine.

30 Other and further important objects of this invention will be apparent from the disclosures in the accompanying drawings and description.

35 The invention (in a preferred form) is illustrated in the drawings and hereinafter more fully described.

In said drawings:

35 Figure 1 is a side view of the finished cup.

Figure 2 is a view on a smaller scale of the opposite side of the cup.

Figure 3 is a top plan view upon the same scale as Figure 1.

40 Figure 4 is a view of the blank from which the cup is made.

Figure 5 is a similar view of the opposite face of the blank.

45 Figure 6 is a view of the partly folded cup showing the result of the first fold.

Figure 7 is a similar view showing the result of the second fold.

Figure 8 is a view similar to Figure 1 of a slightly modified construction.

50 Figure 9 is a view upon a smaller scale of the opposite side of the cup shown in Figure 8.

Figure 10 is a top plan view of the same upon the same scale as Figure 8.

55 Figure 11 is a view of one side of the

blank from which the cup of Figure 8 is made.

Figure 12 is a similar view of the opposite side of the blank.

Figure 13 is a view of the partly formed cup of Figure 8 showing the result of the first fold.

Figure 14 is a similar view showing the result of the second fold.

In said drawings, having particular reference to Figures 1 to 7, the cup is made from a blank having a curved edge 1. The main body of the blank is approximately a sector, one radius of which is the edge 2; the other radial edge 3 of this sector is not the edge of the blank, but the blank continues therefrom to an edge 4, thus forming a flap 5. The line 3 may correspond to actual physical structure, such as a scoring mark or a crease, or it may be merely the location of the fold, so that in the blank before it is folded to make the cup there is no physical structure corresponding to the line 3. The line 6, which bisects the sector, is similar to the line 3 in this respect.

One face of the flap 5 is covered with adhesive, as indicated by the shading in Figure 4. The other face of the flap 5 is not supplied with adhesive, but the corresponding side of the main portion of the blank has a region thereon which is covered with adhesive. This region is located between the lines 3 and 6 near the center of the curve 1, as shown at 7 in Figure 5.

At the center of curvature of the edge 1, a notch is cut in the edge of the blank, as shown at 8. Preferably, the sides of this notch are not straight, but are rounded so that each forms an arc about a center slightly farther from the center of curvature of the edge 1 than are the walls of the notch itself. The result is a star-like form of notch so that the blank has three blunt, rounded projecting points extending into the notch. When the blank is folded by machinery, the points of this star serve to accurately position the blank for starting the several folds.

When forming the cup from this blank, it is first folded along the line 6 to the shape indicated in Figure 6. This fold brings the edge 2 to coincide with the line 3. The flap is next folded along the line 3 to bring the adhesive against the outer face of the margin near the edge 2. When the lap seam

thus formed has had time to become firm, the folding of the cup is completed by folding the point 9 into the position illustrated in Figure 2, where it is secured by means 5 of the adhesive 7.

The creases made in the paper by this last fold are represented by the lines 10, 11 and 12. If it is desired, actual physical structure corresponding to these lines, such as 10 creases or score marks, may be made in the blank before it is folded at all. Also, if it is desired, adhesive 13 may be applied to the region between the line 11 and the notch 8, as illustrated in Figure 4.

15 When the second fold (the fold illustrated in Figure 7) is made, the line of the fold will not cross the line 6 because of the notch 8. Thus no distortion or tearing or other serious strain upon the paper will occur at the 20 notch, and the likelihood of the paper providing a leak at this point is avoided. The notch also gives a rounded instead of a sharp point at 9 in the folded finished cup, with the result that there is no part likely to 25 extend up from the surface of the wall of the cup, and the likelihood of the cup being subject to deterioration from a separation between the folded point and the body of the cup is lessened. Thus leakage either from a 30 tear or from a turned up point is rendered less likely.

In the modified construction, shown in Figures 8 to 14, the blank from which the cup also is made is of the general shape of 35 the sector of a circle, having a curved edge 14 and a radial edge 15. At the other edge the blank does not stop at the radial edge of the sector, but continues to form a flap 16 having an edge 17 parallel to the radial edge 40 18 of the sector.

In Figures 11 and 12 are shown two lines 19 and 20 which divide the sector into three portions, the center portion being half of the area of the sector. These lines may represent 45 actual physical structure, such as scoring marks or creases, for facilitating the folding of the blank to form the cup, but they may also stand for the intended location of the folds and the blank may be made 50 without any actual physical structure corresponding to these lines. The end 21 of the flap 16 is not in line with the radial edge 15, but makes an angle therewith substantially equal to the angle between the edge 15 and the line 20. Lines 22, 23 and 24, forming a 55 portion of a polygon surrounding the center of curvature of the edge 14, may also be actual physical structure as just described or may stand for the intended location of the 60 folds to be described hereafter.

At the center of curvature of the edge 14 the blank is provided with a notch 25. The edges of this notch are not straight but are curved, the convex side of the curve being 65 toward the notch. A star-shape is thus given

to the notch, the points of the star being in line with the lines 19 and 20. The curved edge of the notch 25 opposite the line 22 merges with the oblique end 21 of the flap, but the curved edge at the other side of the 70 notch meets the edge 15 at approximately right angles.

In forming a cup from this blank, the first fold is made along the line 20, as is shown in Figure 13. This results in bringing the 75 edge 15 into coincidence with the bisector of the sector. The next fold is made along the line 19. This result in bringing the edge 18 into coincidence with the edge 15 so that the flap 16 overlaps the margin of the sector 80 near the edge 15.

The point 26 of the cup at the nearer ends of the folds 19 and 20 will not be a sharp point but will be rounded because of the curved character of the edges of the notch 85 25. The final fold in making the cup is made by turning the point 26 up against the body of the cup, as shown in Figure 8. This fold, which is shown at 27, is located upon the superposed lines 22, 23 and 24. The 90 turned-up point 26 is secured to the folded position by means of adhesive 28 on the lower end of the central portion of the sector. In a cup formed in this way the extremity of the point 26 is not sharp but is 95 rounded and consequently is not likely to turn up away from the body of the cup. Moreover, the notch 25, by removing that portion of the material where the folds 19 and 20 would cross one another, does away 100 with the necessity of folding the paper in two directions at once and so it is not likely that the paper will be torn at this point. Because the seam made by the flap 16 overlapping the margin near the edge 15 is not 105 near either the fold 19 or the fold 20, no strain is brought upon the seam made by this flap when the point 26 is folded as described. Consequently, all of the folding may be done at once without waiting for the 110 seam to become firm first.

This case is a continuation and a consolidation of the subjects-matter of two applications filed by me July 3, 1922, Serial Nos. 572,518 and 572,519, for improvements in 115 paper cups.

I am aware that numerous details of construction may be varied through a wide range without departing from the principles of this invention, and I therefore do not pur- 120 pose limiting the patent granted, otherwise than necessitated by the prior art.

I claim as my invention:

1. A blank adapted to be folded for forming folded paper cups, embodying a sector-like body having its straight edges terminating in a point, one edge being adapted to be folded into a flap, said body having a notch in its other edge at the meeting point of the folds. 125 130

2. A blank adapted to be folded for forming folded paper cups, embodying a sector-like body, formed with one of its straight edges longer than the other, said edges terminating in a point, said body having a notch in its longer edge at the point toward which the folds in the body converge. 45
3. A blank adapted to be folded for forming folded paper cups, embodying a sector-like body, formed with one of its straight edges longer than the other, said edges terminating in a point, said body having a multi-pointed notch in its longer edge at the point toward which the folds in the body converge. 50
4. A blank adapted to be folded for forming folded paper cups, embodying a sector-like body, formed with one of its straight edges longer than the other, said body having a multi-pointed notch in its longer edge at the point toward which the folds in the body converge, the points in said notch coinciding with the lines of the folds in said body. 55
5. A blank adapted to be folded for forming folded paper cups, embodying a sector-like body, formed with one of its straight edges longer than the other, said body having a multi-pointed notch in its longer edge at the point toward which the folds in said body converge, the edges of said notch registering when said body is folded to form the point of the cup. 60
6. A blank adapted to be folded for forming folded paper cups, embodying a sector-like body, formed with one of its straight edges longer than the other, said body having a notch in its longer edge at the point toward which the folds in the body converge, the edges of said notch being convexed toward said notch and registering when said body is folded to form the point of the cup. 65
7. A blank for forming flat paper cups, comprising a sector-like body, and a flap ext- 70
- tending from one straight edge thereof, said body having a multi-pointed notch in one straight edge at the center of curvature of said sector, the points in said notch coinciding with the lines of fold, said lines dividing said body in three parts, the area of the central one being approximately equal to the combined area of the other two. 75
8. A blank for forming paper cups including an approximately sector-shaped body, and a flap extending from one radial edge thereof, said blank having a notch at the center of curvature of said sector, the edges of the notch being convex toward the notch so as to form a figure shaped like a fraction of a star, the points of the star being directed toward the radii of the sector which divide the sector into three portions, the area of the central one of which is approximately equal to the combined area of the other two. 80
9. A blank for forming a conical paper cup capable of folding into a flat sector shape and having a seam in the middle of one face, said blank having a main sector-shaped body and a flap along one radial edge and also having a notch at the point of the sector, said notch comprising three curved edges each convex toward the notch whereby the notch has the shape of a fraction of a star having a plurality of points, the curved edges meeting at one of said points being of substantially equal length and the remaining curved edge being of approximately half said length, one of the longer curved edges which is not adjacent the shorter curved edge bounding the flap along approximately half the length of said longer curved edge, and an adjacent part of the sector along the remainder of said longer curved edge. 85

In testimony whereof I have hereunto subscribed my name.

CESARE BARBIERI.
